The ornamental design for a bag toss game as shown and described.

DESCRIPTION

FIG. 1 is a front perspective view of a bag toss game according to the present invention.

FIG. 2 is a top plan view of the bag toss game illustrated in FIG. 1.

FIG. 3 is a bottom plan view of the bag toss game illustrated in FIG. 1.

FIG. 4 is side elevation view of the bag toss game illustrated in FIG. 1.

FIG. 5 is another side elevation view of the bag toss game illustrated in FIG. 1.

FIG. 6 is a front elevation view of the bag toss game illustrated in FIG. 1; and,

FIG. 7 is a rear elevation view of the bag toss game illustrated in FIG. 1.

The broken lines illustrated in FIGS. 1 and 2 represent indicia that forms no part of the claimed invention as defined in FIGS. 1-7.
